CLAIM

The ornamental design for a housing for a test and measurement instrument, as shown and described.

DESCRIPTION

FIG. 1 is a front-side isometric view of a housing for a test and measurement instrument;

FIG. 2 is a rear-side isometric view of the housing for a test and measurement instrument of FIG. 1;

FIG. 3 is a front view of the housing for a test and measurement instrument of FIG. 1;

FIG. 4 is a rear view of the housing for a test and measurement instrument of FIG. 1;

FIG. 5 is a left-side view of the housing for a test and measurement instrument of FIG. 1;

FIG. 6 is a right-side view of the housing for a test and measurement instrument of FIG. 1;

FIG. 7 is a top view of the housing for a test and measurement instrument of FIG. 1;

FIG. 8 is a bottom view of the housing for a test and measurement instrument of FIG. 1;

FIG. 9 is a front-side isometric view of an alternative embodiment of a housing for a test and measurement instrument; and,

FIG. 10 is a front view of the housing for a test and measurement instrument of FIG. 9.

(Continued)

The portions of the housing for a test and measurement instrument shown in broken lines form no part of the claimed design.
